TURBINE DISK

Adrian Albert Lombard and Frederick William Walton Morley, Clitheroe, Christopher Ainsworth Davis, Barnoldswick, and Stanley Clarke Wilkinson, Colne, England, assignors to Rolls-Royce Limited, Derby, England, a British company

Application October 2, 1947, Serial No. 777,506
In Great Britain October 2, 1946

6 Claims. (Cl. 253—39.15)

1

This invention relates to gas-turbines and more particularly to turbine-disc-assemblies of the kind in which the turbine-disc comprises two complementary parts spaced axially and supporting peripherally the turbine-blading therebetween. In such constructions it has been proposed to provide a space between two parts of the disc forming a passage for air cooling the disc and blades and/or their fixing.

In gas-turbine engines for aircraft-propulsion, to which the invention is particularly though not exclusively applicable, it has been the practice to manufacture turbine-discs from solid forgings, which in order to accommodate for high centrifugal loading and to avoid vibration or "whip," have been of relatively thick section. In addition, owing to the elevated temperature at the periphery of the disc it has been necessary to manufacture a disc from special high temperature steels. Such turbine-discs have been cooled by applying air on one face and deflecting the air at the outer periphery of the disc to cool the blade root fixings; in practice, however, such cooling has been relatively ineffective.

The object of the present invention is to provide a turbine-disc and blade-construction which will facilitate manufacture, provide a lighter construction than hitherto and improve the blade or blade-root cooling efficiency.

The nature of the invention will be appreciated by reference to the following description of preferred embodiments illustrated in the accompanying drawings, in which:

Figure 1 is a local radial section through a turbine disc,

Figure 2 is a partial end view of Figure 1 with parts broken away, and

Figures 3 and 4 illustrate an alternative construction of blade mounting.

Referring now to Figures 1 and 2, which illustrate a preferred construction in which each blade is formed with a root to be engaged directly with the halves of the turbine-disc, the turbine-disc comprises two generally similar dished disc parts 40, 41 assembled with their concave faces together. The disc part 40 is formed externally with a flange 42 by which the turbine disc is secured to a hollow shaft 43, and each of the disc parts 40, 41 is centrally bored and has an internal, radially-inwardly directed flange 44 in the bore by which they are bolted together at their centre. A closure plate 45 is secured to the flange 44 on disc part 41 and the flanges 44 are formed with registering slots 46 by which cooling air delivered into the central bore through the

2

shaft 43 is conveyed into the interior of the turbine disc. A sleeve 47 is spigotted on internal shoulders 44a on the disc parts to assist in restraining the disc parts against relative radial movements, and the sleeve 47 is slotted at 48 to register with the outer ends of slots 46. A pair of diametrically-positioned locating-studs 49 are provided on the sleeve 47 to engage in recesses 50 in the shoulders 44a.

10 The periphery of each of the disc parts 40, 41 is thickened to provide an inwardly facing shoulder 51 and the turbine blades 52 are each formed with an inwardly-directed extension 53 on its root with axial extensions or spigot elements 54 to provide shoulders to engage with the shoulders 51 thereby to transmit centrifugal stresses due to the blades 52 to the turbine disc. The two disc parts are secured together by means of rivets 56, although bolts or the like may be used, and the rivets are located on a circle the radius of which is greater than the radius of the annular shoulders 51 so that the rivets are positioned at a point in the turbine disc which is subject to considerably reduced centrifugal stresses. The blade roots 53 are cut away, as will be seen from Figure 2 to permit the passage of the rivets securing the discs together and the thickened portion of the disc peripheries are formed with axially projecting lands 55 which extend between the blade roots and abut one another. The function of the upstanding lands is to determine the spacing of the disc parts at their periphery and to ensure a slight clearance between the inside surface of the thickened periphery and the blade roots to permit the flow of cooling air outwardly between the disc peripheries and the blade roots to cool them. Recesses 57 are formed in the adjacent ends of the blade roots to form channels for the passage of cooling air outwardly to between the thickened peripheral portions of the disc parts 40, 41.

15 The disc parts 40, 41 are also provided at a distance from their centres equal to approximately half their maximum radius with internal axially directed flanges 60 to form sockets to receive a ring 61 which engages in the sockets spigotwise and determines the spacing of the disc parts at this point. Radial air transfer slots 62 are cut in each side face of the ring 61 and transverse channels 63 are formed on the outer face of the ring by features 64 upstanding between the flanges 60, the channels 63 connecting the outer ends of the slots 62 and ensuring mixing of the air streams from the slots to prevent stratification. The upstanding features 64 are connected to one

another between the channels 63 by a narrow strengthening web 65.

A further internal axial flange 66 is provided between the flanges 60 and the thickened periphery to constitute sockets to receive a second spacer ring 67 spigotwise. Air transfer slots 68 are formed in the side faces and outer face of this ring.

The spigot-like couplings between the ring 61 and the disc parts 40, 41, and between the ring 67 and the disc parts and also the coupling provided by the sleeve 47 and shoulders 44a serve to resist the centrifugal gyroscopic or thermal loading tending to cause the discs to move relatively to one another in a radial direction.

The disc parts 40, 41 will conveniently be made from a material such as that known by the trademark "Hykro" and the blades with their integral roots from the material known as "Nimonic" which is capable of withstanding the high temperatures under which it will operate. The rings 61, 67 will conveniently be formed from a material such as aluminium having a high coefficient of expansion so that they will tend to tighten in their sockets as the temperature rises.

In the alternative form of blade root fixing illustrated in Figures 3 and 4, the turbine disc is of similar construction to that illustrated in Figures 1 and 2, and like reference numerals are used in these figures to indicate like parts. The disc parts 40 and 41 are formed as in the previous construction with thickened peripheries to provide shoulders 51 to engage complementary shoulders or spigot elements 54 on the blade roots 53 of the turbine blades 52. The thickened peripheries are also provided with axially-projecting lands 55 to determine the spacing of the discs which are secured together by counter-sunk bolts 56 engaging in nuts 70. The spacing of the disc parts may provide axial clearance in the blade-root fixing for the passage and metering of cooling air.

The disc parts 40, 41 in this construction are formed additionally with annular channels 71 to provide a second shoulder for engaging arcuate projections 72 on the blade roots so that the loading of the disc parts due to the centrifugal stresses generated by the blades is distributed over a greater portion of the disc periphery. The disc securing bolts 56 are positioned on a circle which lies in a portion of the periphery substantially outside the area subjected to these stresses.

It will be appreciated that the constructions of turbine disc above described are relatively light in weight and yet are capable of withstanding the high stresses experienced when in use, are relatively simple to manufacture, and by virtue of the method of blade-root fixing have an improved cooling efficiency as regards the blade-root cooling. Cooling air may also be passed over the outer surfaces of the turbine disc.

For example, as shown in Figures 1 and 2, cooling air may be supplied to the outer faces of the disc-parts as indicated by the arrows. The disc-part 40 may be considered to be on the high pressure side of the turbine whilst the disc-part 41 is on the low pressure side thereof. The cooling air supplied to the face of the disc 40 is thus at high pressure, whilst that supplied to the face of the disc 41 can be at low pressure. The cooling air supplied is preferably metered in such a manner as to provide substantial uniformity of temperature distribution over the two discs and thus avoid, as far as possible, thermal loading tending to displace the disc parts radially relative to one

another. In such an assembly it is preferred to provide a degree of axial nip between the two parts, which will accommodate for the differential pressure existing between the interior of the disc (at relatively high pressure) and the downstream side of the disc part 41 (at relatively low pressure).

Moreover by locating the screws, bolts or rivets for securing the discs together outside the region of the part of their peripheries subjected to high centrifugal stresses, the discs are not unduly weakened by the provision of the holes to receive the bolts, screws or rivets.

Furthermore, the construction of turbine disc of this invention enables the various parts of the disc to be manufactured from a material having the desired strength properties at the temperature at which it will operate. Thus the dished discs may be formed from a material having desired strength properties at a temperature which is moderate as compared with that at which the blading or the blade-supporting ring will operate and the blading or blade-supporting ring will be made from a material having desired strength properties at a more elevated temperature.

What we claim is:

1. An axial flow turbine assembly comprising in combination two complementary disc parts secured to each other and axially spaced to provide a hollow space therebetween; means for supplying cooling gas to said space; peripheral shoulder means on said disc parts extending axially towards one another; a plurality of axial flow turbine blades arranged in circumferential assembly and having blade root portions; and an axially extending circumferential spigot element on each of said blade root portions to engage in radial outward abutment with said axially extending peripheral shoulder means on said disc parts; securing members extending through the disc parts and between adjacent blade root portions and located at a radius outside said spigot elements; spacer means located between adjacent blade root portions to space the disc parts axially independently of said blade root portions; and passages provided between said peripheral shoulder means and said blade root portions and communicating between said space and the exterior of the assembly to permit the flow of cooling gas from said space.

2. An axial flow turbine assembly, comprising in combination two complementary disc parts secured together and axially spaced to provide a hollow space therebetween; means for supplying cooling gas to said space; peripheral shoulder means on said disc parts extending axially towards one another; a plurality of axial flow turbine blades arranged in circumferential assembly and having blade root portions; an axially extending circumferential spigot element on each of

5 said blade root portions to engage in radial outward abutment of the element with said axially extending peripheral shoulder means on said disc parts; securing members extending through the disc parts and between adjacent turbine blade root portions and located at a radius outside said spigot elements, independently of said turbine blade root portions; and interconnecting passages constituted between adjacent turbine blade root portions and between said blade root portions and disc parts by virtue of said independent spacing, which passages communicate between said space

and the exterior of the assembly to permit the flow of cooling gas from said space, such flow cooling the blade root portions and peripheral portions of the discs by direct contact therewith.

3. An axial flow turbine assembly, comprising in combination two complementary disc parts secured together and axially spaced so as to provide a hollow space therebetween; means for supplying cooling gas to said space; peripheral shoulder means on said disc parts extending axially towards one another; a plurality of axial flow turbine blades arranged in circumferential assembly, and having blade root portions; axially extending circumferential spigot elements on each of said blade root portions to engage in radial outward abutment with said axially extending peripheral shoulder means on said disc parts; securing members extending through the disc parts and between adjacent turbine blade root portions and located at a radius outside said spigot elements; axially directed lands circumferentially disposed on said discs to extend between adjacent turbine blade root portions and to interabut to space the disc parts axially at a radius outside said spigot elements independently of said turbine blade root portions, and interconnecting passages constituted between adjacent turbine blade root portions and between said blade root portions and disc parts by virtue of said independent spacing, which passages communicate between said space and the exterior of the assembly to permit the flow of cooling gas from said space, such flow cooling the blade root portions and peripheral portions of the discs by direct contact therewith.

4. An axial-flow turbine assembly comprising in combination a turbine rotor shaft; two complementary disc parts supported by said rotor shaft and axially spaced to provide a hollow space therebetween; means for supplying cooling gas to said space; peripheral shoulder means on said disc parts extending axially towards one another; a plurality of axial flow turbine blades arranged in circumferential assembly and having blade root portions; axially extending circumferential spigot elements one on each of said blade root portions to engage in radial outward abutment of said spigot elements with said axially extending peripheral shoulder means on said disc parts; securing members extending through the disc parts and between adjacent blade root portions and located at a radius outside said spigot elements; means for spacing the disc parts axially at a radius adjacent said securing means independently of said turbine blade root portions; axial abutment means on said disc parts defining said axial spacing at an inner radius adjacent the radius of the shaft; circumferential shoulder means on said disc parts extending axially into said space and located at a radius between said peripheral shoulder means and said abutment means; a spacer ring in said space engaged in axial abutment by said disc parts and to engage in radial outward abutment with said circumferential shoulders; passages formed in said ring to permit the passage of cooling gas radially outward through said ring; and interconnecting passages constituted between adjacent blade root portions and between said blade root portions and disc parts by virtue of said independent spacing, which passages communicate between said space and the exterior of the assembly to permit the flow of cooling gas from said space, such flow cooling the blade root portions and peripheral portions of the discs by direct contact therewith.

5. An axial flow turbine assembly comprising in combination two complementary disc parts secured together and axially spaced to provide a hollow space therebetween; means for supplying cooling gas to said space; first peripheral shoulder means on said disc parts extending axially towards one another; second peripheral shoulder means on said disc parts extending axially towards one another and located at a radius outside said first peripheral shoulder means; a plurality of axial flow turbine blades arranged in circumferential assembly and each having blade root portions; a first axially extending circumferential spigot element on each of said blade root portions to engage in radial outward abutment of the element with said first peripheral shoulder means; a second circumferential spigot element on each of said blade root portions to engage in radial outward abutment of the element with said second peripheral shoulder means; securing members extending through the disc parts and between adjacent turbine blade root portions and located at a radius between the first and second peripheral shoulder means; spacer means located between adjacent blade root portions to space the disc parts axially at a radius outside said first spigot elements independently of said turbine blade root portions; and interconnecting passages constituted between adjacent turbine blade root portions and between said blade root portions and said disc parts by virtue of said independent spacing which passages communicate between said space and the exterior of the assembly to permit the flow of cooling gas from said space, such flow cooling the blade root portions and peripheral portions of the discs by direct contact therewith.

6. An axial flow turbine assembly comprising in combination a turbine rotor shaft; two complementary disc parts supported by said rotor shaft and axially spaced to provide a hollow space therebetween; means for supplying cooling gas to said space; peripheral shoulder means on said disc parts extending axially towards one another; a plurality of axial flow turbine blades arranged in circumferential assembly and having blade root portions; axially extending circumferential spigot elements one on each of said blade root portions to engage in radial outward abutment of said spigot elements with said axially extending peripheral shoulder means on said disc parts; securing members extending through the disc parts and between adjacent blade root portions and located at a radius outside said spigot elements; spacer means located between adjacent blade root portions to space the disc parts axially at a radius outside said spigot elements independently of said turbine blade root portions; axial abutment means on said disc parts defining said axial spacing at an inner radius adjacent the radius of the shaft; circumferential shoulder means on said disc part extending axially into said space and located at a radius between said peripheral shoulder means and said abutment means; a spacer ring in said space engaged in axial abutment by said disc parts to engage in radial outward abutment with said circumferential shoulders; passages formed in said ring to permit the passage of cooling gas radially outward through said ring and interconnecting passages constituted between adjacent blade root portions and between said blade root portions and disc parts by virtue of said independent spacing which passages communicate between the said space and exterior of the assembly to permit the

flow of cooling gas from said space, such flow cooling the blade root portions and peripheral portions of the discs by direct contact therewith.
